ADJUSTABLE BED COVER SUPPORT

Joseph A. Voss, Denver, Colo.

Application July 13, 1942, Serial No. 450,674

4 Claims. (Cl. 5—319)

1

This invention relates to a bed cover support and more particularly to a portable, rigid, and adjustable frame member for positioning adjacent a bed in operative relation to its covers to define a patient receiving conditioning chamber, although it may be employed with equal advantages for other purposes.

It contemplates more especially a portable, adjustable, and compact device which is capable of association with a bed for defining an aerated patient-receiving chamber in conjunction with the bed covers to more effectively treat and more speedily heal surface afflictions such as burns, wounds, surgical incisions, skin diseases, surface ulcers due to toxic or other internal disturbances, and provide greater comfort by supporting the bed clothes out of contact with a person supported in a lying position on a bed or the like.

Numerous types of devices intended for the treatment of patients confined to bed without any bed clothes in direct contact with the body, have heretofore been proposed. These devices have not proven entirely satisfactory from the standpoint that they are cumbersome, entail a great deal of work on the part of the attendants, do not provide for a convenient bed clothes change nor accessibility to the patient to take care of their normal routine needs. These known devices are otherwise unsatisfactory from the consideration that hospital attendants are overtaxed in their routine so that hospital and convalescing appliances of all kinds cannot be advantageously used unless utilizable with minimum time and labor requirements by a single nurse or those who extend care to patients.

With the teachings of the present invention, a portable self-sustaining, readily movable, and highly effective bed cover support has been provided which may be easily shifted for positioning adjacent a bed and relative to the bed clothes thereon to define a patient-receiving compartment which is readily formed and dismantled for easy patient access, depending upon the requirements of and providing for the regular patient routine without entailing any appreciable time, inconvenience, or effort on the part of the attendant.

The flexibility of its adaptation is highly advantageous for the purposes set forth in the treatment, convalescing, and attendance of bed confined patients without any of the disadvantages incident to known devices intended for a similar purpose and requiring more than one attendant to manipulate. The ready formation of a patient-receiving bed chamber and its effective dis-

2

placement as well as reformation, affords the full advantages thereof without impairing access to the patient to meet routine attending requirements. Then, too, the extraordinary compactness thereof as well as its collapsibility during inoperation, are highly advantageous in order that the device may be instantly available without requiring any appreciable space or offering storage problems while not in use.

- 10 These features coupled with self-contained accessories desirable to condition and maintain the patient-receiving bed chamber under proper control for the exposure of the patient's body thereto, provides a highly desirable unit that assists in the care, comfort and more speedy recovery of patients. The structural features and their ease of operation, enables a single attendant or for that matter the patient to utilize the teachings of the present invention without entailing any appreciable time, effort or inconvenience along with the other customary duties and services required to be rendered in the care of afflicted individuals.

One object of the present invention is to simplify the construction and to improve the operation of devices of the character mentioned.

Another object is to provide a self-contained bed clothes support that is compact, easily adjustable for adaptation to a bed in the formation of a patient-receiving chamber, and readily portable for removal to enable access to the patient to furnish routine daily requirements.

Still another object is to provide a bed clothes support that is adjustably connected to a stand movably supported for ready association and removal relative to a bed to provide a conditioning chamber in conjunction with the bed clothes.

A further object is to provide an arcuate bed clothes support in adjustable association with a portable stand serving as a mount therefor to a bed to define a patient receiving compartment.

A further object is to provide an arcuate frame to support the bed clothes relative to the mattress so that it can be readily associated and removed to provide a conditioning chamber without obstructing possible access to the patient or requiring any involved adjustment thereof for that purpose.

A still further object is to provide a compact, 50 portable standard having an arcuate bed clothes support member operatively connected therewith for different positions of adjustment to define a patient receiving conditioning chamber that is readily removable for access to the patient without substantially disturbing the bed clothes which

are available for ready compartment reformation after the attendant has fulfilled routine care requirements.

Still a further object is to provide conditioning instrumentalities in conjunction with a patient receiving compartment defining a portable unit capable of association and removal relative to a bed to provide the advantages of maintaining bed clothes out of contact with the patient while affording ready access for routine requirements.

Other objects and advantages will appear from an illustrated embodiment of the present invention.

In the drawings:

Figure 1 is a side view in elevation of a device embodying features of the present invention illustrated in association with a bed mattress to clarify the showing.

Figure 2 is a sectional view taken along line II—II of Figure 1.

Figure 3 is a fragmentary sectional view taken substantially along line III—III of Figure 1.

Figure 4 is a fragmentary sectional view taken substantially along line IV—IV of Figure 3.

Figure 5 is a schematic electric wiring diagram of the bed chamber conditioning instrumentalities comprising part of the assembled unit shown in Figure 1.

Figure 6 is a front view of a switch panel viewed substantially from lines VI—VI of Figure 1.

Figure 7 is a plan view of the bed clothes supporting frame which defines a patient receiving bed compartment.

Figure 8 is a large fragmentary plan view of an outer rib expandable portion of the arcuate frame shown in Figure 7, parts thereof being shown in section to clarify the showing.

Figure 9 is a sectional view of the ventilator motor and mount taken substantially along line IX—IX of Figure 7.

Figure 10 is a fragmentary sectional view taken substantially along line X—X of Figure 7.

Figure 11 is a fragmentary front view of a pivotal connection between the bed clothes supporting frame and the standard.

Figure 12 is an end view on the pivotal connection shown in Figure 11.

Figure 13 is a fragmentary sectional view of the shank portion of the arcuate frame taken substantially along line XIII—XIII of Figure 7.

Figure 14 is a fragmentary sectional view of the frame shank and switch housing taken substantially along line XIV—XIV of Figure 1.

The structure selected for illustration is not intended to serve as a limitation upon the scope or teachings of the invention, but is merely illustrative thereof. There may be considerable variations and adaptations of all or part of the teachings depending upon the dictates of commercial practice.

The present embodiment comprises a base 10, in this instance having angularly disposed tripod forming arms 11, 12, and 13, which are formed integral with each other at their point of intersection to comprise a part of a linear stabilizing arm 14 disposed normal to the arm 12. As shown, the linear stabilizing arm 14 is formed integral with the arm 12 at its free extremity to divide the arm 14 to extend the same distance on both sides of the tripod arm 12.

In order to render the base 10 with its stabilizing arm 14 readily movable along a supporting surface such as a floor and to enable it to effectively serve as a support for instrumentalities to be hereinafter described, roller casters 15 are piv-

otally connected to the extremities 16 of the tripod arms 11—13 and the stabilizing arm 14.

To this end, the base 10 has an upstanding tubular boss 17 formed integral therewith at the juncture of the tripod arm 12 with the linear stabilizing arm 14 to provide a vertical bearing having tubular standard 18 which is telescopically received in the tubular boss 17. The elongated tubular standard 18 is held in the tubular upstanding boss 17 by means of a suitable fastening expedient such as a threaded stud 19 which has a knurled enlarged head 20 to afford convenient finger manipulation of the stud 19 so that the tubular standard 18 may be readily removed or attached depending upon the requirements of any particular situation.

A solid elongated rod 21 of somewhat smaller diameter than the interior bore of the tubular standard 18 is telescopically associated therewith, for vertical extensive adjustment relative thereto for support therein. To this end, the upper peripheral edge 22 of the tubular standard 18 is flanged to provide a reinforced orifice for the reception of the solid rod 21 and to afford increased lateral support therefor. So that the solid rod 21 may be maintained at any desired vertical position of displacement relative to the tubular standard 18, a threaded stud 23 is disposed transversely through the tubular standard 18 approximate to the upper flanged orifice 22 thereof, so that engagement can be effected with the elongated rod 21 to effect its support in any position of telescopic displacement relative to the tubular standard 18 within the limits of their respective lengths.

So that the threaded stud 23 may be readily manipulated, an enlarged knurled head 24 is provided on the threaded stud 23 so that it may be rotated in one direction or the other to accomplish its intended purpose. It should be noted that the threaded stud 19 (Figures 3 and 4) registers with an annular groove 25 provided in the bottom solid portion 26 of the tubular standard 18 so that the latter may be rotated at any desired position relative to the base 10 without permitting its removal from the tubular boss 17.

The solid elongated rod 21 terminates upwardly in an enlarged shoulder 27 which is joined to a bearing end 28 of an offset arm 29. The offset arm 29 is cast or otherwise shaped from material to provide a lateral reinforcing rib 30 that terminates in a circular plate 31. The circular plate 31 is adapted to confront a correspondingly shaped plate 32 which is formed integral with an angularly disposed shank 33. The shank 33 terminates in an arcuate bracket 34 which overhangs the base 10 for an appreciable distance so that the shank 33 with its integral connecting bracket 34 will extend for a distance commensurate with the width of a hospital bed. It should be noted that the overhanging bracket has a substantially I-shaped cross section (Figure 14) to provide rigidity, supporting capacity, and lateral channels 35—36 for the reception of wires 37—38, respectively, utilized to provide electric energy to instrumentalities supported by the bracket 34 as will appear more fully hereinafter.

In order to pivotally support the bracket 34 relative to the offset arm 29, the confronting circular plates 31—32 are provided with aligned axial apertures which receive a threaded bolt 39 therethrough. The bolt 39 has a threaded nut 40 engaging the free extremity thereof on the offset side to retain the plates 31—32 in confronting contact for rotation relative to each

other. In order to limit the pivotal displacement of the bracket 34 relative to the offset arm 29 to assume different positions of adjustment for operative and inoperative positioning, depending upon the requirements of any particular situation, the stationary circular plate 31 is provided with an arcuate slot 41 extending therethrough to receive a stud 42 which is reciprocally mounted in an aperture 43 provided in the circular plate 32.

The stud 42 terminates in an enlarged knurled head 44 beyond an ear 45 having an aperture 46 in alignment with the aperture 43 to reciprocally support the stud 42 therethrough.

A spring 46' envelops the stud 42 between the ear 45 and a pin 47 extending transversely through the stud 42 to serve as a stop for the spring 46. This serves to normally urge the stud 42 into the arcuate slot 41 so that normally the bracket 34 will be displaceable about the bolt 39 serving as a pivotal mount within the limits of the slot 42.

One extreme position of the stud 42 within the slot 41 coincident with the engagement of the stud 42 with the extreme counter-clockwise extremities thereof (viewed from Figure 1) will bring the bracket 34 to its operative overhanging position relative to a bed mattress 48 supported by its spring frame 49, while the engagement of the stud 42 with the opposite extreme end of the slot 41 will place the bracket 34 in an operative inclined position (Figure 11) away from the bed mattress 48 to afford access thereto.

To lower the bracket 34 to its extreme counter-clockwise position (shown in dotted outline in Figure 1) so that its free extremity 50 very closely approaches the base 10 to minimize the space requirements thereof for storage during non-usage, the attendant withdraws the stud 42 against the urge of the spring 46 by grasping the knurled head 44 and removing the stud 42 from the arcuate slot 41 to permit the circular plate 32 of the bracket 34 to rotate relative to the plate 31 and permit the bracket 34 to be displaced downwardly for support by the base 10 (dotted outline position, Figure 1). In this position, the entire unit occupies very little space and can be moved into a closet or unoccupied corner of a room.

The arcuate bracket 34 has confronting curved hooks 51 and 52 formed integral therewith at the extreme ends thereof to receive the tubular rods 53-54 of a flexible bed clothes supporting frame or flexible surface member 55. To this end, the curved hook 51 is formed integral with the bracket 34 at its point of juncture with the shank 33 (Figure 1), while the curved confronting hook 52 is formed integral with the bracket 34. The tubular frame rods 53-54 are normally separated for a distance somewhat greater than the spread between the confronting hooks 51-52, and this is accomplished by means of a plurality of clamps 56-57 provided along each of the tubular rods 53-54 (Figure 7). In this instance, each of the tubular rods 53-54 have four uniformly spaced and permanently anchored clamps 56-57, respectively, and two movable associated clamps 58-59 and 60-61 that slide on the rods 53-54, respectively.

The clamps 56-57, 58-60, and 59-61 receive a plurality of flexible wires 62, in this instance three, projecting between each pair of the confronting clamps 56-57, 58-60 and 59-61 for permanent attachment therebetween to collectively define an open flexible surface member or framework for the support of bed clothes. It

should be noted that the clamps 58-60 and 59-61 are adjustably connected to the adjacent permanently attached clamps 56-57 and approximate to the ends of the rods 53-54 by means of wire links 63-64 pivotally connected about their looped extremities 65 by means of a flanged stud 66. The other looped extremities 67-68 of the links 63-64 respectively, are pivotally connected to flanged studs 69-70 anchored to the permanently attached and movable clamps 56-57, 58-60, and 59-61 so that the movable clamps can be displaced relative to the tubular rods 53-54 to receive somewhat smaller rod extensions 71-72 telescoped in both ends of the tubular rods 53-54, respectively.

The movable clamps 58-59 and 60-61 are fixed to the extremities of the telescopic rods 71-72 to permit the expansive displacement of the end clamps 58-60 and 59-61 to correspondingly displace the plurality of flexible wires 62 mounted therebetween to define an open surface member for the support of bed clothes thereon. This affords the expansive adjustment of the bed clothes supporting frame 55 to extend over the thorax alone or therebeyond to include the legs 25 of the patient, depending upon the affliction or the treatment as well as the extent thereof. The bracket 34, frame 55, and wires 62 constitute a bed clothes supporting framework.

In applying the flexible surface member or frame 55 over a bed, the rod standard 21 is first adjusted to the desired height so that the lower edge of the offset bracket web 29 will be in line with the top of the mattress 48 (Figure 1), and thereupon, the base 10 is displaced transversely of its length so that the bracket 34 with its bed clothes supporting frame 55 will overlie the mattress width 48. The bed clothes are supported above the patient by the frame 55 that is sprung to assume an even greater arcuate configuration. Then the bracket 34 by virtue of the removable association of the frame 55 between the confronting hooks 51-52, the flexible frame 55 being sprung into position therebetween, so that the bed clothes will overhang the standards 18-21 along that particular side of the bed mattress 48.

So that the bed clothes will be held against the edge 13 of the mattress 48 to avoid the admittance of air therebetween, an arcuate fork 74 of substantially U-shaped configuration braces the enlarged shoulder 27 of the extensive rod 21 to clamp the bed clothes therebetween.

The fork 74 constitutes an offset extremity of a vertical arm 75 that is pivoted at its lower extremity 76 to a clamp 77 that is anchored around the tubular standard 18 approximate to the vertical boss 17 comprising part of the base 10. A spring 78 is anchored as at 79 to the clamp 77 while its other extremity 80 is anchored to the vertical arm 75 to normally urge the latter in a counter-clockwise direction (viewed from Figure 1) to maintain a bed clothes clamp about the shoulder 27 of the vertical standard extension 21, thereby precluding an upward movement of air into the patient receiving chamber device above the mattress 48 by the flexible frame 55 and its support 34. Then, too, the fork 74 serves to anchor the bed clothes so that they will be maintained in their desired position without slipping off to the floor.

So that the flexible frame that is sprung between the bracket hooks 51-52 will not be accidentally removed or displaced, a retaining hinge 75 81 is attached to the bracket 34 approximate to

the hook 51 so that the angularly shaped movable hinge plate 82 (Figure 13) can be displaced downwardly in a clockwise direction (viewed from Figure 13) to engage the frame rod 53 against the hook 51 and preclude its removal therefrom. To remove the flexible frame 55, the hinge plate 82 is pivotally displaced in a counter-clockwise direction (viewed from Figure 13) and the frame is sprung inwardly to narrow the spread thereof sufficiently to clear the hooks 51-52 and permit its withdrawal to assume a straight plane contour by virtue of the flexible rods 62 that normally assume their linear shape.

The conditioning instrumentalities that preferably though not essentially are associated with the bracket 34 beneath the clothes supporting and chamber defining frame 55, may comprise opposing electric sockets 83 supported by a clamp 84 that has flanges 85 affording the attachment thereto to the under surface of the frame 34 (Figure 10) through the medium of suitable fasteners such as machine screws 86. The opposing sockets 83 are disposed transversely of the frame 34 to receive suitable conditioning or therapeutic bulbs depending upon the dictates of medical requirements. In the present embodiment, the opposing sockets 83 receive elongated light bulbs 87-88 which are screwed therein in the customary manner to emanate light rays of ordinary intensity for exposure of the patient's skin thereto.

Artificial light from electric bulbs is known to possess beneficial effects upon the skin which effectively serve to dry afflicted areas and otherwise have a desirable general therapeutic reaction. Wire screen guards 89-90 are somewhat larger than and shaped to conform with the bulbs 87-88 for threaded engagement as at 91 with the opposing sockets 83 to completely envelop the bulbs 87-88 as a protection against contact therewith. The screen guards 89-90 are of tubular construction and are properly reinforced by rigid end enclosures 91' and circular interiorly threaded and channeled rings 92 defining an open orifice therefor for the reception of the bulbs 87-88 therethrough.

The opposing sockets 83 are suitably connected to insulated triple leads 93 which project through the clamp 84 and extend along the lateral channels 35-36 of the bracket 34 for connection to the leads 37-38 (see Figure 5) extending therealong (Figure 14).

Another important conditioning instrumentality comprises, in this instance, a minute electric fan 94 (Figure 9) that is powered by an electric motor 95 having its armature shaft 96 in operative connection with the fan 94. The motor 95 is of a very small frictional horsepower capacity and is resiliently suspended by springs 97-98 anchored to the motor 95 by the lower ends and attached to depending studs 99-100 which project through resilient shock absorbers such as rubber discs 101 to effectively support the motor 95 against vibration relative to a bracket plate 102. The bracket plate 102 has an upstanding shank 103 of substantially I-shaped cross section to afford its attachment underside of the bracket 34 laterally of and approximate to the electric light socket clamp 84. It should be noted that the motor 95 is so mounted as to position the fan 94 thereabove to create a very slight movement of air downwardly and laterally to effect a very minute circulation of air under the covers supported by the resilient frame 55. This provides a very compact and noiseless motor 95 to operate

the fan 94 so that the gases and odors known to result from body afflictions may never become stagnant and surface wounds will always be exposed to fresh air without chilling or subjecting the patient to undesirable drafts.

So that there will be no possible physical contact with the fan 94 and its motor 95, a cylindrical wire mesh receptacle guard 104 is shaped to provide a reinforcing circular band 105 at its open end which is complementary to the bracket plate 102 for attachment thereto by means of any suitable fastener such as machine screws 106. This enables the convenient removal of the guard 104 for cleaning, repair, and replacement should the occasion arise for access to the fan 94 and its motor 95. Suitable links 107-108 (Figure 5) connect the motor 95 to the power leads 37-38 that extend outwardly (Figure 1) from a switch housing 109. The switch housing 109 is of substantially U-shaped configuration to serve as a complement of the I-shaped bracket 34 for frictional displacement thereover to enclose all of the leads extending along the side channels thereof (Figure 14).

It should be noted that the lead 108 that extends from one terminal of the motor 95, is connected in series with a rheostat or electric resistance 110 to substantially reduce the speed of the fan 94 so that the amount of aeration will be of an exceedingly minute character to avoid undesirable exposure of the patient, and yet sufficiently to keep the surface of the patient's body exposed to fresh air for feeding purposes and to expel all odors as well as undesirable gases when the fan 94 is in operation.

The switch housing 109 carries a switch plate 111 (Figure 6) which has three switches 112, 113 and 114 mounted thereon in conjunction with a service plug 115. The switches 112-113-114 control, in this instance, the electric bulbs 87-88 and the electric motor 95, respectively (Figure 5). The electric service plug 115 is connected across lines 37-38 to provide a convenient electric outlet for auxiliary apparatus that may be utilized in the treatment of the patient. With this arrangement, either or both lights 87-88 may be placed in operation independent of or in conjunction with the motor 95, depending upon the dictates of the attendant and the requirement of the patient. As shown, another cylindrical receptacle guard 116 having a reinforced circular band 117 at its upper end, is shaped to conform in size and appearance with the motor guard 104 for connection to a bracket similar in construction to the one described in connection with the guard 104 so that the wire mesh receptacle 116 may be suspended from the frame bracket 34 approximate to the bulbs 87-88 on the side opposite to the motor guard 104 to present a symmetrical arrangement of instrumentalities.

The wire mesh receptacle 116 may be utilized for any purpose such as to confine a deodorant, germicide or antiseptic, depending upon the needs of any particular situation. The wire mesh receptacle 116 is attached to its bracket by means of threaded fasteners 118 extending through the reinforced mount ring 117 in much the same manner as the fasteners 106 serving to support the motor guard 104 to render both detachable. A thermometer 119 is supported by end brackets 120-121 that are suitably attached to the frame bracket 34 to provide an indication of the temperature within the patient receiving chamber defined by the bed clothes supported by the frame 55. This will determine the desirability of utilizing

ing the lights 87-88 that have some influence on the temperature to which the patient's body is subjected.

It should be noted that the bed clothes are held on the resilient frame 55 which defines the contour thereof for overhanging engagement with the standards 18-21. The substantially U-shaped clamp 74 securely holds the bed clothes against the shoulder 27 of the telescopic rod 21 to preclude slipping of the bed clothes downwardly. Then, too, the retention of the bed clothes on the frame 55 enables the latter to be pivotally shifted to its upward position for access to the patient lying on the mattress 48 without appreciably disturbing the bed clothes. Upon giving the patient the desired service or care demanded by the occasion, the frame 55 with its bracket 34 can then be returned to its operative position (solid line outlined in Figure 1) without requiring the bed clothes to be rearranged as they are returned to their initial operative position without distortion or accidental displacement.

With the arrangement of parts above described, it will be apparent that the bed clothes supporting frame 55 can be easily removed for cleansing, sterilization, and dismantling purposes. Additionally, the telescopic standards 18-21 are readily removable from the base 10, and the frame bracket 34 detached from the offset arm 29 which is a part of the upper telescopic rod 21. These parts can be conveniently packed for long time storage or shipment from the factory.

Additionally, it should be observed that the teachings of the present invention primarily contemplates a bed support that is independent of the bed and mattress. Consequently, the patient can leave the bed without assistance to take care of personal needs and afford freedom to patients who are not helpless. This can be accomplished without materially disturbing the bed clothes or the apparatus that serves as the support therefor. Then, too, the patient is relieved of the consciousness of disturbing the bed with every slight movement which a patient is bound to make in abundance because of the necessary relaxing of muscles and change of posture. With devices of known construction, the mattress served as a support for the chamber defining instrumentalities so that the patient not only was actually restricted in freedom of movement, but was kept consciously aware of the necessity to avoid movement. Even slight movement of the patient on the mattress would cause the directly supported patient defining chamber to move therewith and create a possible undesirable physical change in position as well as mentally affect the composure of the patient confined therein.

While I have illustrated and described a preferred embodiment of this invention, it must be understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

1. In a device of the character described, the combination with a support for overhanging a bed mattress in spaced confronting relation therewith, of a surface member attached to said support for supporting bed clothes to define a patient receiving chamber with said bed mat-

ress, and an extension on said surface member to vary the bed clothes supporting surface thereof and the size of the patient receiving chamber defined therewith.

- 5 2. In a device of the character described, the combination with a standard for extending upwardly above a bed mattress, of a rigid open framework extending from said standard to overhang a bed mattress in spaced confronting relation therewith for supporting bed clothes to define a patient receiving chamber with said bed mattress, said framework comprising a rigid supporting arm pivoted to said standard, and a flexible surface member on said rigid supporting arm, said flexible surface member being sprung into predetermined shape on and conforming to the shape of said rigid arm for retention thereon to support the bed clothes above the mattress.
- 10 3. In a device of the character described, the combination with a standard for extending above a bed mattress, of a rigid open framework pivotally connected to said standard to overhang a bed mattress in spaced confronting relation therewith for supporting bed clothes to define a patient receiving chamber with said bed mattress, said framework comprising a rigid supporting pivoted arm and a flexible frame sprung from its normal expanse into predetermined shape for retention on said rigid arm, and end
- 15 25 30 35 40 45 extensions on said flexible frame adjustably connected therewith to vary the bed clothes supporting expanse thereof and the size of the patient receiving chamber defined therewith.
4. In a device of the character described, the combination with a standard extending upwardly above a bed mattress, of a rigid open framework extending from said standard to overhang a bed mattress in spaced confronting relation therewith for supporting bed clothes thereover to define a patient receiving chamber with said bed mattress, and means for retaining the bed clothes against said standard and against the mattress edge adjacent thereto for minimizing the uncontrolled movement of air in said patient defining chamber.
